CLAIM

The ornamental design for a corner connector for furniture, as shown and described.

DESCRIPTION

FIG. 1 is a top perspective view of a corner connector for furniture showing my new design;

FIG. 2 is a side elevational view thereof;

FIG. 3 is a top plan view thereof; and

FIG. 4 is a bottom plan view thereof.

The device is trisymmetric in the sense that three sides are identical in appearance to FIGS. 2 and 3, the other three sides being identical in appearance to FIG. 4.
